United States Patent

Des. 239,657
Patented Apr. 20, 1976

239,657

RADIO

Hoi Tong Vong, Hong Kong, assignor to Asia
International Electronics Ltd., Hong Kong

Filed May 22, 1974, Ser. No. 472,098

Claims priority, application Great Britain Nov. 28, 1973

Term of patent 14 years

Int. Cl. D14—03

U.S. Cl. D56—4 B

FIG. 1.

FIG. 2.

FIG. 3.

FIG.4.FIG. 1 is a front, top and right side perspective view of a radio showing my new design with the lid in open position;

FIG. 2 is a rear elevational view thereof;

FIG. 3 is a front, bottom and left side perspective view with the lid in closed position; and

FIG. 4 is a top plan view with the lid in open position.

The unshown top surface, rear of the lid and upper portion of the rear of the base are flat plane surfaces.

I claim:

The ornamental design for a radio, substantially as shown and described.
